United States Patent Office

Des. 185,143
Patented May 12, 1959

185,143

ATOMIZER

Karl Flury, Adliswil, Zurich, Switzerland, assignor to Delfensor Aktiengesellschaft, Zurich, Switzerland, a corporation of Switzerland

Application January 2, 1959, Serial No. 54,024

Term of patent 7 years

(Cl. D83—1)

Fig. 1 is a perspective view looking downwardly on the atomizer at an angle to horizontal of about 30°,
Fig. 2 is a top plan view of the atomizer, and
Fig. 3 is a side elevation view of the atomizer.
I claim:
The ornamental design for an atomizer, as shown.
